UNITED STATES PATENT OFFICE.

HARRIET A. PARKER, OF BOSTON, MASSACHUSETTS, ASSIGNOR TO THE ROXBURY CARPET COMPANY, OF SAME PLACE.

DESIGN FOR A CARPET.

SPECIFICATION forming part of Design No. 14,479, dated December 11, 1883.

Application filed October 23, 1883. Term of patent 3½ years.

To all whom it may concern:

Be it known that I, HARRIET A. PARKER, of Boston, in the county of Suffolk and State of Massachusetts, have invented a new and original Design for Carpets, of which the following is a specification.

The nature of my design is fully shown in the accompanying photographic illustration.

The design is composed of the variously formed angular and other shaped figures and the intervening floral and foliage ornamentation, as shown.

I claim—

The design for a carpet, substantially as shown and described.

In testimony whereof I have signed my name to this specification, in the presence of two subscribing witnesses, this 16th day of October, 1883.

HARRIET A. PARKER.
